UNITED STATES PATENT OFFICE.

MINNIE C. MOUSER, OF SAN DIEGO, CALIFORNIA.

TATTING-HOOK.

1,379,930.

Specification of Letters Patent. Patented May 31, 1921.

Application filed December 6, 1917. Serial No. 205,817.

To all whom it may concern:

Be it known that I, MINNIE C. MOUSER, a citizen of the United States, residing at San Diego, in the county of San Diego and State 5 of California, have invented certain new and useful Improvements in Tatting-Hooks, of which the following is a specification.

This invention relates to improvements in 10 tatting hooks and it is the dominant object of the invention to provide a device for enabling the user of the same to readily engage and temporarily hold the thread during a tatting operation, thereby materially expediting the work.

15 Other objects will be in part obvious and in part pointed out hereinafter.

Other and further improvements and 20 novel details in the construction of the device will be appreciated from the description to follow, which, for a clear understanding of the invention should be considered in connection with the accompanying drawings forming a part hereof, and 25 wherein the preferred embodiment of the invention is shown for the purpose of illustration.

In the drawings:—

Figure 1 is a perspective of the improved hook, and,

30 Fig. 2 is a vertical section through the same.

Similar characters of reference refer to similar parts throughout the several views of the drawings.

35 Referring now more particularly to the drawings, 1 represents a tapered cap or thimble, the upper end of the same, obviously, being closed and having a laterally extending hook 2 secured thereto by suitable

means, the stem of the hook being elongated, 40 for a purpose which will be hereinafter apparent. It is to be also noted, that the hooked outer end of the member 2 is pointed as at 3, thereby permitting the same to be readily engaged or inserted between 45 stitches during the tatting operation.

When using the improved tatting hook, the cap or thimble would in most cases be arranged on the little finger of the user's right hand, as the hook is employed as a 50 means of drawing the thread through the picots to connect with the shuttle in tatting, thereby saving the necessity of laying down the shuttle or disarranging the work in any way. The pointed portion 3 can also be 55 used for removing extra stitches often made by mistake in tatting, which can be easily and quickly removed without laying down the shuttle, or in any way disarranging the work.

Manifestly, the construction shown is capable of considerable modification and such modification as is within the scope of my claim, I consider within the spirit of my invention.

60 I claim:—

A tatting device including a finger engaging thimble, a straight stem projecting from the closed end of the thimble in longitudinal alinement with the longitudinal 70 axis of said thimble, said stem being sharply pointed at its outer end and being provided with a barb having a rearwardly directed point and which merges into the pointed end of the stem.

75 In testimony whereof, I affix my signature hereto.

MINNIE C. MOUSER.
